DENTAL MATRIX INSTRUMENT

Alfred E. Hanssen, Chicago, Ill.

Application October 11, 1937, Serial No. 168,357

4 Claims. (Cl. 32—63)

My invention relates to a novel construction of a matrix, the face of which is adaptable and adjustable, and the principal object of the invention is to provide a matrix that will serve as means for inserting, confining, and uniformly condensing plastic dental filling materials into cavities located in the labial and buccal and lingual surfaces of teeth, and especially such cavities as are known to the dental profession by the name of gingival third cavities.

Another object of the invention is to provide a matrix face which will mold plastic filling materials so that when they set or harden the filling thus produced will have an outer surface which conforms to and reproduces the natural contour formerly possessed by the restored area or surface of the tooth.

Another object of the invention is to provide a matrix which will furnish the plastic filling materials with smooth and highly finished surfaces when said materials set or harden while in contact with the matrix face.

Another object of the invention is to provide protection for plastic porcelain and cement filling materials from moisture in the mouth during the setting or hardening process.

Another object of the invention is to provide means for carrying plastic filling materials into dental cavities.

For the purpose of illustrating my invention, I have shown in the accompanying drawing one form thereof, which is at present preferred by me, because the same has been found to give satisfactory and reliable results in actual practice. It is to be understood that the various instrumentalities of which my invention consists can be variously arranged and organized and that my invention is not limited to the precise arrangement and organization of these instrumentalities as herein shown and described.

In describing my invention in detail, reference will be had to the accompanying drawing wherein like characters denote like or corresponding parts throughout the several views, and in which:

Figure 1 is a full view of the instrument with the arms 6 closed so as to give a definite contour to the matrix 5.

Figure 2 is a sectional view of the instrument showing the various parts in their relative positions and with the inner barrel 2 partly withdrawn to give the matrix 5 its natural form.

Figure 3 is a sectional view of the outer barrel 1 so as to show the arm operating slot 11.

Figure 4 is a plan view of the matrix 5 with one shape of face 22.

Figure 5 is a sectional view of the inner barrel 2. Figure 6 is a side view and a partial section of the matrix rod 10.

Figure 7 is a side view of arm 6.

Figure 8 is a plan view of the outer barrel 1 showing slot 11 in which arms 6 move inward or outward as controlled by inner barrel 2 and spring 7.

In these views, 1 indicates the outer barrel into which fits inner barrel 2. Thumb nut 3 seats in channel 13 of the inner barrel 2 and when engaged with thread 21 said thumb nut 3 moves rod 10 longitudinally in channel 23. Through outer barrel 1 are set pivots 4 about which are pivoted arms 6. One end of spring 7 exerts pressure against tips 8 on arms 6 and the other end of spring 7 seats in channel 12 in inner barrel 2. Tips 8 rest against slots 17 in rod 10 and thus rod 10 is kept from turning and also, after being assembled, is kept within a limited range of longitudinal movement. Matrix 5 consists of face 22 to which is attached screw 9 which engages with threads 18 in rod 10. The threads 15 on inner barrel 2 engage with threads 16 in outer barrel 1. When inner barrel 2 is turned counterclockwise bevel 14 contacts bevel 19 of arms 6 and causes them to move into slots 11 in outer barrel 1, so that by these movements bevels 20 of arms 6 will contact matrix 5 near its center. Knurl 24 on outer barrel 1 facilitates handling by furnishing a surface that is easily gripped.

The operation of the instrument is as follows:

As the matrix 5 will be supplied in various sizes, and its face 22 made of various materials and combination of materials, one is chosen which face 22, covers and fits most nearly the tooth area or surface to be filled. The peripheral outline form is trimmed to fit, with scissors. When placed upon the tooth the entire periphery of face 22 should rest upon the tooth structure adjacent to the cavity margins. The fitted matrix is laid aside and the holder is next adjusted. This is done by turning thumb nut 3 clockwise thereby withdrawing rod 10 until its threaded end 18 is within barrel 1 and thus out of the way. By turning knurled end of barrel 2 as shown in Figure 1 counterclockwise, the beveled ends 20 of arms 6 will be brought to meet. In this position ends 20 of arms 6 are placed over the cavity or tooth surface to be filled, and by moving inner barrel 2 clockwise end 20 of arm 6 are allowed to part until ends 20 rest upon the tooth structure adjacent to the cavity margins and those margins preferably which are located about the area of greatest width mesio-distally. Removing the in-

strument from the patient's mouth, thumb nut 3 is now moved counterclockwise until end 18 of rod 10 projects beyond ends 20 of arms 6, thus allowing matrix 5 to be attached to rod 10, screw 9 being engaged by thread 18. Thumb nut 3 is then turned clockwise thereby drawing matrix 5 towards arms 6 until their ends 20 touches face 22 of matrix 5. The instrument is now carried back to the mouth and face 22 of matrix 5 is placed over tooth area to be filled and held in the same position as when the detached matrix 5 was first fitted as to outline form. With the face 22 of matrix 5 thus in place on the tooth, thumb nut 3 is moved clockwise thereby drawing matrix 5 closely against arms 6 until face 22 receives and forms a concave contour which rests uniformly upon the convex surface of the tooth.

With the instrument adjusted and the matrix adapted and adjusted as described, the intended filling material in a plastic condition is placed upon the concave surface of face 22 and carried into the cavity. Pressure is applied by the operator and the filling material is evenly condensed and adapted to all of the cavity walls and cavity margins. In case the gingival (gum) cavity margin extends under the free margin of the gum, then the thin edge of the matrix is slipped or placed under said gum margin, as previously fitted to do, and a close adaptation of the filling material is thus caused along such gingival cavity margins. That action of my matrix is very advantageous in the manipulation of plastic filling materials and especially so where enamel or porcelain cements are used.

Said action is not obtainable by means commonly used. It is common practice to insert plastic filling materials by means of spatulas and plugger shaped points and then, in case of porcelain cements, to cover the material with a strip of Celluloid which is held in place by finger pressure. It is not possible thus to obtain an accurate adaptation of the filling material along all the cavity walls and margins and especially so the gingival cavity margin, which is crescent shaped as to outline form, as well as being cut into and along a convex tooth surface. Due to these circumstances, the commonly used method of filling such cavities results in a bulky surplus of material being found about one or more margins of the filling. This surplus material must be removed by grinding after the filling material has set or hardened. My invention overcomes these objectionable features and will be of great practical value in the manipulation of all plastic materials used in connection with such cavities. Thus in the formation of inlay patterns made of wax, in inserting temporary stoppings, in the formation of silver amalgam fillings, and in the application of medicines and drugs to tooth surfaces, in all such manipulations my invention will be found very practical and useful.

While I have chosen to show the form of the holder and the arrangement of the barrels and nut illustrated, it will be evident that a great variety of these might be made use of for obtain-

ing part of the benefit of my invention and that other forms of combinations than the double barrel and pair of arms might be made use of to secure common adjusting and adapting means.

Having described my invention what is claimed is:

1. A dental matrix instrument comprising a matrix consisting of a thin deformable plaque provided with central holding means, a hollow handle, a rod adapted for longitudinal movement within the handle, and provided with means cooperating with the matrix-holding means to fix the matrix, at least one lever pivotally mounted on the handle and engaging the marginal portion of the matrix plaque and means engaging the opposite end of the lever for forcing the matrix-engaging end of the lever in an adjustable matrix-deforming position whereby the matrix may be conformed to any desired tooth surface.

2. A dental matrix instrument operative solely by a thrusting force applied to its handle, comprising a thin normally flat matrix plaque, flexible, but tending to return to flattened position, means centrally located on said plaque for attaching it to a thrust rod, a thrust rod attached thereto, a handle and adjustable means cooperating with the handle and thrust rod to secure the matrix plaque in an adjustably flexed position conforming to the curvature of a tooth surface.

3. A dental matrix instrument comprising a matrix plaque provided with central attaching means, a matrix holding rod with cooperating means for receiving the attaching means, an outer barrel, an inner barrel for longitudinal movement within said outer barrel, cooperating means associated with said barrels for holding said barrel in fixed longitudinal relation to each other, lever arms pivoted to said outer barrel and engageable with marginal portions of the matrix plaque, spring means seated on the inner barrel normally urging the lever arms out of engagement with the matrix plaque, and adjustable means for moving the matrix-holding rod longitudinally within said inner barrel whereby the lever arms may be brought into adjustably controlled engagement with the matrix plaque to hold it conformed to a curved tooth surface.

4. A dental matrix instrument having a matrix conformable to a tooth surface independently of the tooth comprising a flexible matrix plaque having the inherent property of returning to shape when flexing stress is removed, means central of the plaque for securing it to holding means, fingers associated with the holding means for flexing the outer portion of the plaque to conform it to the desired curvature of the tooth, and means for urging the fingers into and out of engagement with the plaque, said last mentioned means including means engaging the plaque-holding means to adjust the plaque to conform to a tooth surface and to maintain the plaque in adjusted position.

ALFRED E. HANSSEN.
